Primary Examiner — Michael A. Pratt(74) *Attorney, Agent, or Firm* — Laabs Intellectual Property(57) **CLAIM**

The ornamental design for an archery stabilizer bracket as shown and described.

DESCRIPTION

FIG. 1 is a front-left angled view of an archery stabilizer bracket, showing the new design.

FIG. 2 is a front view thereof.

FIG. 3 is a back view thereof.

FIG. 4 is a right-side view thereof.

FIG. 5 is a left-side view thereof.

FIG. 6 is a top view thereof; and,

FIG. 7 is a bottom view thereof.

The dash-dot broken lines in the Figures depict boundaries of the claimed design. The dashed lines in the Figures depict unclaimed portions of the device and are for illustrative purposes only. The broken lines form no part of the claimed design.

1 Claim, 7 Drawing Sheets(56)
